ATTORNEYS

UNITED STATES PATENT OFFICE.

LEONARD ROUQUART, OF NEW YORK, N. Y.

DESIGN FOR A TEAPOT OR SIMILAR ARTICLE.

No. 38,706.

Specification for Design.

Patented July 30, 1907.

Application filed June 27, 1907. Serial No. 381,179. Term of patent 3½ years.

To all whom it may concern:

Be it known that I, LEONARD ROUQUART, a citizen of the United States, residing in the city of New York, borough of Manhattan, in the county and State of New York, have invented a new, original, and ornamental Design for a Teapot or Similar Article, of which the following is a specification, reference being had to the accompanying drawing, forming a part thereof.

Figure 1 is a side elevation of a teapot showing my new design; and Fig. 2 is a plan view of the same.

I claim:

The ornamental design for a teapot, or similar article as shown.

LEONARD ROUQUART.
